US0D1095927S

(12) **United States Design Patent** (10) Patent No.: **US D1,095,927 S**
(45) Date of Patent: ** Sep. 30, 2025

(54) **CEILING LAMP**

(71) Applicant: **Congying Ruan**, Fangchenggang (CN)

(72) Inventor: **Congying Ruan**, Fangchenggang (CN)

(**) Term: **15 Years**

(21) Appl. No.: **29/993,395**

(22) Filed: **Mar. 14, 2025**

(51) LOC (15) Cl. **26-05**

(52) U.S. Cl.

USPC **D26/72; D26/2**

(58) **Field of Classification Search**

USPC D26/1, 2, 59, 72, 80, 88, 89; D23/370, D23/379, 381, 382

CPC F21S 8/03; F21S 8/033; F21S 8/036; F21S 9/03; F21S 9/037
